UNITED STATES PATENT OFFICE.

HERBERT TREFZGER, OF MELROSE PARK, ILLINOIS, ASSIGNOR TO THE RICHARDSON COMPANY, OF LOCKLAND, OHIO, A CORPORATION OF OHIO.

PROCESS OF LOADING BATTERY BOXES.

Application filed July 18, 1925. Serial No. 43,988.

My invention relates to processes of loading battery boxes for shipment and particularly to processes of loading battery boxes in bulk in freight cars.

5 It is the object of my improved process to load battery boxes in freight cars in such manner that the percentage of breakage will be reduced to a minimum and that the structure of boxes will be so strengthened that it 10 will be possible to increase the number of boxes which can be loaded in a car thereby allowing a considerable saving in freight.

Specifically it is my object to load battery boxes in cars in alternately raised and normally disposed tiers with horizontal rows nested and so braced against each other as to provide a balanced thrust which will avoid undue strain on any particular row or tier or at any particular position on each 20 box.

The usefulness of my process of loading is well evidenced by the fact that the percentage of breakage in cars loaded with battery boxes in bulk has been reduced from 25 two to three per cent to a slight fraction of one per cent with the consequent probability that a decreased freight rate will be allowed due to the improved strength of the disposal of the load within the car when 30 the car is loaded in accordance with the preferred arrangement hereinafter described and claimed.

Referring to the drawings in which I have shown diagrammatically the principle 35 by which I accomplish my improved loading process:—

Figure 1 is a perspective view of the particular type of battery box which I have been most successful in loading.

40 Figure 2 is an end sectional view within the car.

Figure 3 is a detail end section showing my preferred arrangement of nesting with a suitable spacing between inverted handles 45 of one row and the compartment and side walls of the next adjacent underneatn row.

Figure 4 is a longitudinal section taken from within a car.

Generally indicated at 1 is a battery box 50 with which size and shape I have had the most satisfactory results. The box has handles 2 on each of the end sides of the box, and compartment walls 3 which in this type of box divides the inner part of 55 the box into three compartments or cells.

In former practice the boxes were placed in tiers and alternate rows of two nested boxes extending lengthwise across the width of the car. From a brief consideration of this plan of loading it will be realized that each tier and each series of alternately inverted and normal rows were independent of any reinforcement except a horizontal side and end bracing, and the result was that all the strain of the load exerted a 60 thrust on the series of rows on the floor of the car which resulted in frequent breakage. 65

In my novel process the first row in the car is placed lengthways across the width of the car as indicated by the diagrammatic representation of the boxes at 4, 4, in Figures 2 and 3. The next row of boxes is placed in inverted position on top of the first row as indicated at 5, 5, with the handles of the inverted boxes interspaced from 70 the side and compartment walls of the boxes in the first row. In Figure 3 the spacing of the two sets of handles of inverted boxes from the end walls of the upright boxes in which the handles extend is indicated 75 at A and the spacing from the compartment walls of the upright boxes as indicated at B. The tier of boxes may be made up of as many layers or rows of boxes as practical depending on the dimensions of the 80 type of box being loaded. As indicated in Figure 2 each tier within the car is made up of a plurality of alternately upright and inverted boxes extending with their length 85 across the width of the car. 90

The approximate dimensions of the boxes illustrated, may be considered seven inches wide, seven and three quarters inches deep and nine inches long with the space between the end walls and the compartment walls 95 approximately two and a quarter inches. The thickness of the handles is approximately one half inch so that correctly interspaced the handles of boxes in inverted rows, will be in the center between the end 100 and compartment walls of the boxes with which they are nested, so that the distance represented by the dimensions A and B in Figure 3 should be about five eighths of an inch. This gives ample clearance so that 105 with side strains the boxes will not have any tendency to break off at the handle portions.

To avoid the tendency for longitudinal stress in the car causing a great strain on 110

the top portions of the boxes, I have provided that alternating tiers are elevated from the floor of the car as indicated in Figure 4. This is of particular importance as there is a tendency for the boxes to have a slightly tapered shape which it will be readily seen would cause great strain if all the tops came in horizontal rows. By alternating the horizontal line of the tops of each row of boxes in each alternating tier I thus balance the longitudinal thrust within the car so that there is no more crushing tendency at one position on the boxes than at another.

In order to retain the rows and tiers I have invented a plan of disposing, preferably wooden, braces to hold the boxes in position in accordance with my loading arrangement. To provide for the elevating of alternate tiers I arrange to dispose blocks of wood (shown in section at C in Figure 4), at intervals across the car corresponding to the approximate center of each alternate tier and I secure boards D to the blocks so that the support for the boxes is yielding. This prevents any tendency to crush due to sudden jolts of the car. In actual practice with boxes of dimensions similar to the type illustrated I have found that a total elevation of the block and the board should bring the alternate rows about three and one half inches higher than the corresponding non-elevated rows, which distance seems to fairly well distribute the strain due to longitudinal thrust within the car.

In order to support the boxes in each alternate row I have found that if the first row is placed in the car with the ends of the boxes abutting a side wall and the next two rows above secured in position with blocks as indicated at E in Figure 2 with boards F so that the boxes in the alternate row will be about three and a half inches to one side, this distance provides sufficient offset to interspace the handles between the ends and compartment walls of the nested boxes.

It seldom happens that the first row of boxes extends clear across the car so that filler blocks or boards G are usually necessary and may be suitably secured as indicated in Figure 2; the blocks H extend from the filler pieces and support the boards J which extend longitudinally in the car, which boards support the alternate pairs of rows comprising one row inverted and one row right side up on top of the inverted row. The blocks E and boards F yieldingly support alternate adjacent rows on the opposite side of the car. Thus, with my preferred arrangement of loading, no row is braced in positive alignment with any other row and each row is supported in the car with at least one dimension facing a side board yieldingly retained on blocks. It is further of advantage to stagger the posi-

tion of the rows of blocks on one side as compared with the rows of blocks on the other.

This arrangement of battery boxes in a car is adaptable for packing boxes in any kind of rectangular outer casing, without departing from the principle of my invention. Other sizes and shapes of boxes may also be packed in a similar alternately staggered and nested manner.

It will be readily understood that in loading a car in accordance with my invention the nesting and staggering horizontally in combination with a vertical staggering of alternate tiers transform the entire load into a single unit. Hitherto boxes were placed in rows and tiers all upon the same level. Thus the load could easily be broken up into separate units, or divisions, by planes passing along the junctions of the boxes either in horizontal or vertical rows. When the car swayed in either direction these several units shifted and moved one over the other with the very obvious effect of tending to destroy the boxes both by the natural abrasion of such movements and also by the fact that when an entire section of the load of one tier shifted on another considerable momentum was gained by the mass movement and whenever a single handle was opposed to this momentum the handle was invariably cracked off or crushed.

Although the shape of a battery box is unusual I expect to claim broadly the unit load principle which is clearly disclosed in the foregoing specification.

Having thus described my invention, what I claim as new and desire to secure by Letters Patent, is:—

1. That process of packing open topped boxes with handles projecting upward from the bodies of the boxes, in a traction vehicle of rectangular cross section which consists in disposing the boxes in a plurality of rows comprising a bottom layer of boxes in upright position, with a plurality of layers of boxes above the bottom layer, each in inverted position with relation to the next succeeding layer beneath it, and the handles of boxes in successive layers projecting into oppositely disposed boxes in adjacent layers, and each succeeding row disposed in horizontally staggered relation to adjacent rows, with the layers in the rows and the rows in the rectangular traction vehicle braced to form a unit load with the longitudinal layers in the rows in interlocked groups, and with the lines of the sides, tops or bottoms of boxes in adjacent rows in alignment.

2. That process of packing battery boxes for shipment in a car which consists in disposing the boxes lengthwise in a plurality of tiers across the car, arranging a plurality of rows of boxes one above the other in each tier, with the boxes in each row invert-

ed with relation to the boxes in the row under it, and with the handles of boxes in each row extending within boxes in adjacent rows, and disposing alternate tiers in raised position and providing bracing from the walls of the car to retain the rows and tiers in said disposed and arranged position.

3. That process of packing battery boxes for shipment in a car which consists in disposing the boxes lengthwise in a plurality of tiers across the car, arranging a plurality of rows of boxes one above the other in each tier, with the boxes in each row inverted with relation to the boxes in the row under it, and with the handles of boxes in each row extending within boxes in adjacent rows and disposing alternate tiers in raised position and providing bracing from the walls of the car to retain the rows and tiers in said disposed and arranged position, said bracing comprising blocks extended from walls of the car with strips supported by the blocks bearing against the walls of the boxes.

25 4. That process of packing battery boxes
for shipment in a car which consists in dis-
posing the boxes in tiers of rows, the rows
comprising a plurality of nested boxes with
handles of the boxes extending within open-
30 ings in boxes facing them in adjacent rows,
vertically staggering the alternate tiers and
supporting the tiers with strips extending
from the floor of the car across the car
under every alternately staggered tier and
35 bracing the rows from the sides in said
staggered position.

5. That process of packing battery boxes for shipment in a car which consists in disposing the boxes in tiers of rows, the rows comprising a plurality of nested boxes with handles of the boxes extending within openings in boxes facing them in adjacent rows, vertically staggering the alternate tiers and supporting the tiers with strips extending from the floor of the car across the car

under every alternately staggered tier and
bracing the rows from the sides in said
staggered position, said strips comprising
blocks extending from the floor of the car
with wooden strips to support the vertically
staggered tiers. 50

6. That process of packing battery boxes for shipment in a car which consists in disposing the boxes in nested rows with the handles extended within boxes in adjacent rows interspaced from the end and compartment walls thereof, and strips to support the rows in such position. 55

7. That process of packing battery boxes for shipment in a car which consists in disposing the boxes in nested rows with the handles extended within boxes in adjacent rows interspaced from the end and compartment walls thereof, and providing yielding means to support the rows in such position, elevating alternate rows in the car and providing yielding means for supporting the alternately elevated rows.

8. That process of packing battery boxes for shipment in a car which consists in disposing strips to hold rows of nested boxes in tiers of rows of alternately inverted and upright rows of boxes, with the handles of the boxes in the rows extended within boxes in adjacent rows and interspaced from end and compartment walls of the boxes in said adjacent rows.

9. That process of packing battery boxes for shipment in a car which consists in disposing strips to hold rows of nested boxes in tiers of rows of alternately inverted and upright rows of boxes, with the handles of the boxes in the rows extended within boxes in adjacent rows and interspaced from end and compartment walls of the boxes in said adjacent rows, and providing blocks to support the strips to permit them to bear yieldingly against the rows of boxes.

HERBERT TREFZGER.
